(57) **CLAIM**

The ornamental design for a package for a foot care product, as shown and described.

DESCRIPTION

FIG. 1 is a perspective view of a package for a foot care product in a closed condition;

FIG. 2 is a front elevation view thereof;

FIG. 3 is a rear elevation view thereof;

FIG. 4 is a side view thereof;

FIG. 5 is an opposing side view of FIG. 4;

FIG. 6 is a top plan view thereof;

FIG. 7 is a bottom plan view thereof;

FIG. 8 is a perspective view of a package for a foot care product in an open condition;

FIG. 9 is a front elevation view thereof;

FIG. 10 is a rear elevation view thereof;

FIG. 11 is a side view thereof;

FIG. 12 is an opposing side view of FIG. 11;

FIG. 13 is a top plan view thereof; and,

FIG. 14 is a bottom plan view thereof.

The dash-dash broken lines depict portions of the package for a foot care product that form no part of the claimed design. The dash-dot-dash broken line in FIGS. 8 and 9, designating the boundary of the claimed design, forms no part of the claimed design.

1 Claim, 10 Drawing Sheets
